Inventor,
Walter E. Trufant,

By his attorney
Attest:

UNITED STATES PATENT OFFICE.

WALTER E. TRUFANT, OF WHITMAN, MASSACHUSETTS, ASSIGNOR, BY MESNE ASSIGNMENTS, TO KRENTLER-ARNOLD HINGE LAST COMPANY, OF DETROIT, MICHIGAN, A CORPORATION OF MICHIGAN.

LAST.

Patented Dec. 31, 1907.

No. 875,186.

Specification of Letters Patent.

Application filed April 21, 1898. Serial No. 673,338.

To all whom it may concern:

Be it known that I, WALTER E. TRUFANT, of Whitman, in the county of Plymouth and State of Massachusetts, have invented certain new and useful Improvements in Lasts, of which the following is a specification.

My invention relates to lasts which are transversely divided at or near the shank into sections and adapted to shorten by a relative movement of the sections so as to be readily removed from the shoe, and has for its object to provide a simple and strong means for connecting the sections and locking them in their lengthened position.

I have devised a number of improvements, one for locking the last in lengthened position, another for hinging the last parts together, another for releasing the last parts from locked position, etc., and have invented a construction which combines all these improvements in a one-piece construction, which is preferable on account of its simplicity, cheapness, strength and durability.

In the accompanying drawings Figure 1 is a side view of my last locked in its lengthened position with a portion broken away. Fig. 2 is a section through the line $y-y'$, Fig. 1. Fig. 3 shows the last with the heel raised ready to swing forward. Fig. 4 shows the last with the heel swung forward ready to remove the last from the shoe. Figs. 5 and 6 are two views of an unlocking spindle.

In all the views like characters refer to the same parts.

The general shape and construction of the last itself may be of any usual or preferred kind, the form thereof herein shown consisting of a fore-part a and a rear-part b divided along a broken diagonal line $r-r'$ for permitting the heel-part to slide and swing upon the fore-part, the heel-part having a usual spindle socket p .

In the preferred form of my invention herein shown, I provide central vertical saw cuts or kerfs extending inwardly from the abutting walls of the last-parts, in which is mounted a link or plate-like hinge member c pivoted in the fore-part on a transverse pin f and in the heel-part on a similar pin g . As already stated, I prefer to combine all the features of my invention in this one member c and have therefore provided at its lower edge a slot or notch i operating as a latch to catch over a pin or keeper h and at its upper portion a hole l opposite an elongated slot m through the side of the last for receiving a hook (not shown) by means of which the plate, or combined hinge member and locking device, c , may be pulled or pushed to the right or left within the last, Fig. 1, as desired, and coöperating with the pin f , I have provided a slot e, e' , the part e' of said slot extending very nearly concentric to the pivot g to permit said plate to be shifted within the last as stated.

For the purpose of retaining the member c in its shifted position and permitting the last to be quickly unlocked, I prefer to provide an arm d extending backwardly from the plate c to the bottom of the spindle hole p , said arm being herein shown as carrying a spring j for normally pressing the same frictionally against the last and adapted to spring out over a projection q , as shown in Figs. 1 and 2, when the last is in locked position, but capable of being quickly retracted from said position by the engagement of a lip o of a tool n when the latter is rotated in the spindle socket.

I regard it as new to provide a combined lock-and-hinge member shiftable within the last, and also I regard it as new to have a lock attached to the two sections of the last. It is also new to operate this lock by a movement thereof towards the bottom of the parts hinged together.

Another important feature of my invention resides in securing a wedge-like action for binding the parts together.

In a co-pending application, Ser. No. 674,143 filed on a joint invention by myself and another, we have explained the difficulty in properly locking a hinged last together due to the shrinkage of the wood, and have therein provided one form of locking device for overcoming this difficulty. Accordingly, I have herein set forth another means of securing the same end, and for that purpose have made the locking device wedge-shaped, by extending the surface of the slot e' which bears against the pin f not quite concentric to the pin g , as will be clearly evident from the drawings where the same is slightly exaggerated for clearness of illustration, so that as a result, the farther to the left the plate c is pushed within the last, the more tightly will the fore-part and heel-part be wedged or locked into rigid, lengthened position.

In the specific construction shown, the

slot *e*' is slightly inclined relatively to the pivot *g* so that as the slot travels over the pin *f* in locking the last sections together, the latter are brought nearer together, the farther 5 the plate *c* is rotated and hence the more firmly the sections are held together.

The slot *e* is provided so that when the plate *c* is rotated to unlock the last, the last-parts will still be connected together so as not 10 to fall apart, said slot allowing the sections to slide on one another and permitting the heel-part to swing forward. The last can not be collapsed until the member *c* has been slightly rotated on the pin *g* to unlock the 15 last and bring the slot *e* into line with the pin *f* and substantially parallel with the direction of collapsing movement. Great strength for resisting the downward pressure when the last is in use bottom up is provided by 20 having the three pins widely separated, the pin *f* being above the center line of the last, *h* below the same and *g* nearer thereto so that strains brought upon the last tending to pull or spring the last sections apart are resisted 25 by the pin *g* in the heel section and the pins *f* and *h* in the toe section, and said sections can not slide on one another to shorten the last because the inclination of the slot *e*' operates rather, when the last is locked, to draw 30 the sections more tightly together. The wedge-surface of the inner side of the slot *e*' crowds the heel pivot *g* and the pin *f* apart and hence binds the bottom secant surfaces tighter, the separating effort of pins *g* and *f* 35 serving to pinch or draw together more tightly the bottom front wall of the heel part and the bottom rear wall of the forepart.

I do not confine myself to the spring *j* for holding the parts, but may use any suitable 40 means under conditions of light use, or, when the last is simply left in the shoe, it may be omitted and also the arm *d* may be left off, the plate *c* being simply operated by the hook inserted through the side opening *m*.

45 I have already sufficiently described the operation of my invention in connection with the description of its construction; it will be observed that the arrangement of the slotted connection and its securing devices is such 50 that the slot permits the pins *f* and *g* to approach each other as the last collapses.

As already intimated, one feature of my hinged last resides in providing means which permits the last to move from its working position into its shortened position without first 55 lengthening, and this result is secured by providing the hinging connection or link (that being the form of hinge member herein shown) with ability to move in the last, the 60 idea being to have relative movement of the heel-part with relation to said link or hinging device, so as to bring the parts into such relative position that the heel-part may be moved into its shortened position without first moving 65 rearwardly.

It will be evident that, inasmuch as the two pivots *f* and *g* of the plate-hinge member or link *c* are not in horizontal alinement, but the pin *f* is nearer the top of the last, it would be impossible for the said hinging device *c* to 70 turn on the pin *f* as a center without swinging the heel-part rearwardly and thereby lengthening the last before it shortens, but by having the hinge plate *c* swing at different times on the pins *f* and *g* and providing relative movement between the hinge and last, this difficulty is obviated and the last is collapsed without first lengthening. 75

As already explained, I prefer to have a sliding movement between the fore-part and heel-part, and for this reason have provided the lower or longer portion *e* of the slot.

What I claim as my present invention and desire to secure by Letters Patent, is—

1. A last, comprising two sections having 85 opposed sliding faces, a movable latch pivotally secured in one of said sections and projecting into the other section, said latch being formed with a slot, and a pin on the other section occupying said slot.

2. A hinged last comprising two sections, a movable member pivotally secured in one of said sections and projecting into the other section, said member being formed with a slot extending in the general direction of 95 swinging movement of said member, and a pin on the other section occupying said slot when the sections are locked.

3. A last comprising two sections having 100 opposed sliding faces, a movable member pivoted to one of said sections and formed with a slot having a pin-guiding portion and a pin-locking portion, the former movable into parallelism with said faces by rotation of said member, and a pin on the other section occupying said slot.

4. A hinged last, comprising two sections, a latch pivotally connected to both sections, and means co-operating with said latch for locking said sections rigidly together in 110 lengthened position.

5. A hinged last comprising a fore section and a heel section, the latter being formed with a spindle socket, said sections having opposed sliding faces, a latch pivoted to said heel section and arranged for release by the spindle entering said socket, said latch projecting into the fore section, and a complementary locking member or keeper on the fore section.

6. A hinged last, comprising two sections, a movable latch pivotally secured in one of said sections and projecting into the other section, said latch being formed with a slot having a pin-locking portion, and a pin on 125 the other section occupying said slot, and means for locking said latch when said pin-locking portion is engaged with said pin.

7. A last comprising a fore-section and a heel-section, the latter being formed with a 130

spindle socket having a shoulder near the bottom, a latch pivoted to said heel section and having an arm extending into the socket and arranged for release through said socket, 5 said arm carrying means to engage with said shoulder to lock the latch.

8. A divided last, having a heel part, a vertical plate fastened to the heel part and provided with a slot and notch, the fore part 10 being provided with two transverse pins for cooperation with the said slot and notch to connect the heel part with the fore part.

9. A divided last, having its fore part and heel part separated by a diagonal cut for 15 sliding shortening movement, a vertical plate fastened to one of said parts and provided with a slot and notch, the other of said parts being provided with two transverse pins for cooperation with the said slot 20 and notch to connect the heel part with the fore part.

10. A last, comprising a heel-part and a fore-part hinged together, a hinge in the form of a plate secured by two pins, one pin 25 in the fore part and one pin in the heel-part, adapted to turn on said pins, said plate being approximately circular in shape and standing vertically in recesses provided in the parts of the last, said plate and heel-part having 30 means including a slot for permitting relative movement of said plate and heel-part on said pivot-pin to enable the last to shorten readily.

11. A hinged last, having its two sections 35 connected by a combined lock and hinge-member shiftable within the last, constructed to permit said shifting movement and including means operating, upon the occurrence of said movement, to lock the sections 40 together.

12. A hinged last, having its two sections hinged together for movement into collapsed and lengthened position, and a lock comprising a pin in one section and a movable plate 45 standing edgewise vertically in the last pivotally mounted in the other section, said plate embracing said pin, and having means operating, upon movement of said plate within the last, to lock or unlock the parts 50 thereof.

13. A hinged last, having a locking member hinging the two sections of the last together, and means permitting the moving of said locking member for locking and unlocking 55 said sections.

14. A hinged last, having a locking device attached to the two sections of the last, and a member for unlocking, by movement toward the sole, said locking device.

15. In a hinged last, a plate within the last, a pivotal connection for said plate with one last-part, a pivot-and-slide connection for said plate with the other last-part, and means cooperating with said plate for locking 60 the last in lengthened position.

16. In a hinged last, a vertical plate connection pivotally mounted in both the heel-part and the fore-part, the pivotal connection in one of said parts consisting of a slot and pin to permit the plate both to slide and 75 to turn, the plate also having a notch, and the last having means for removably engaging the notch.

17. A hinged last, having a heelpart, and a forepart, a vertical plate joining said parts, 75 the portion of the plate normally occupying the forepart having a notch and an elongated slot, the last having a complementary member for engaging said notch, a pivot pin in the forepart passing through said slot, and a 80 pivot pin passing through said plate in the heelpart.

18. In a hinged last, a locking device pivoted in the heel-part and provided with a wedging slot, and a stationary pin in the 85 fore-part occupying said slot, movement of said locking device in the last locking the bottom of the fore-part and heel-part tightly together.

19. A hinged last, provided with a locking 90 device having a sliding movement in the last and secured to the fore-part and to the heel-part, said locking device having an inclined surface for engaging the fore-part of the last and wedging against the same when moved 95 toward locking position.

20. A hinged last, containing a locking device having a sliding connection with the last, said locking device having an inclined surface for engaging the fore-part of the last and wedging against the same when moved toward locking position, and a spring for normally holding said locking device in locking position.

21. A last comprising a fore-part and a 100 heel-part, the latter being formed with a spindle socket, a latch pivoted to said heel-section and having an arm extending into the socket and arranged for release through said socket, and means carried by said arm for normally holding said latch against movement.

22. A hinged last, having a slotted connection for connecting the parts together, securing devices cooperating with said connection 110 for holding the parts together in lengthened position, said securing devices being located in the last with reference to the slot in said connection to provide for the approach of said securing devices in collapsing the last, 120 and means cooperating with said connection for locking the last parts in locking position.

In testimony whereof I have affixed my signature, in presence of two witnesses.

WALTER E. TRUFANT.
